C. G. DEMING

AUTOMATIC WINDOW FASTENER

Filed April 30, 1925

FIG. 1.

Charles Gaylord Deming

INVENTOR

Patented Dec. 14, 1926.

1,611,104

UNITED STATES PATENT OFFICE.

CHARLES GAYLORD DEMING, OF PEEKSKILL, NEW YORK.

AUTOMATIC WINDOW FASTENER.

Application filed April 30, 1925. Serial No. 27,082.

The present invention relates to improvements to fastening devices for windows. In carrying out my invention I propose to provide a simple and effective fastener comprising two elements which may be attached to the meeting rails of the window, and which will automatically engage each other to fasten both of the sashes. I also propose to provide a device, which may be readily attached to the meeting rails of the upper and lower sashes, and adapted to automatically move into locking position when the sashes are closed upon the frame. It is a still further object of my invention to provide means for automatically latching two sashes when the same are closed, which shall embody the desirable features of simplicity in construction, cheapness of manufacture and accuracy in operation. My invention also prevents the window from rattling when the sashes are closed. Frequently windows are closed, but not latched or secured. My device automatically secures the sashes together when the sashes are closed.

Referring to the drawings:

Fig. 1. Is an end view of my invention, showing the two heads in latched position.

Fig. 2. Is a perspective view of my invention showing the latched position on the meeting rails of the sashes.

My invention consists of two metal plates having heads bent in the form of an acute angle, each fitting exactly into the other, and having at their operative extremities short right angled portions bent inwardly to form a latching means. The inner plate is of spring metal. The outer part is fastened to the top face of the meeting rail of the lower sash (E), the inner part being fastened to the top face of the meeting rail of the upper sash (F). In the drawings A represents the outer part, and (B) the inner part. C C' represent the short right angled portions bent inwardly at the extremities of each part. D is the opening in the outer part, through which the inner part is pressed by the finger, thus detaching the parts when the window is desired to be open. When the meeting rails come together, the sashes are automatically latched, and the spring B draws the meeting rails together and prevents the rattle of the window. The two heads or parts may be fastened to the meeting rails in any desirable way.

What I claim is:

1. In combination with the inner edge of the meeting rail of the lower sash, a metal plate having a head bent inwardly in the form of an acute angle, and having at its operative extremity a short right angled catch portion bent inwardly and having its other end provided with a right angled extension, outwardly, as a fastening piece.

2. In combination with the outer edge of the meeting rails of sashes, a keeper plate mounted on the upper rail of the lower sash and provided with a head, a plate of spring metal having a head of the same width as the keeper mounted on the lower rail of the upper sash to coact with the keeper, and bent inwardly in the form of an acute angle, to fit the keeper exactly and having at its operative end a short, right angled catch portion bent inwardly, and having its other end provided with a right angled extension, as a fastening piece.

3. In combination with the meeting rails of sashes, a pair of retainers, one of which is secured to the meeting rail of the inner sash and projects outwardly, and which is provided at its operative extremity with a right angled catch portion bent inwardly, forming a securing means, the other being attached to the meeting rail of the lower sash and having an acute angled head, with a right angled bend at its operative extremity, adapted to pass over the head of the inner retainer when the windows are closed.

4. The structure set forth in claim 3, the outer head being provided with an opening large enough to allow the depression of the inner right angled catch portion out of place by an operator's finger and thus release the windows to be opened.

5. The combination with the meeting rails of sashes of a pair of retainers, formed from plate metal, the inner one of spring metal; the one attached to the meeting rail of the upper sash adapted to project inwardly, and having at its operative extremity a short right angled catch portion bent inwardly, as a latching means; the other, or outer metal retainer, being attached to the meeting rail of the lower sash and having a head formed similar to that of the inner retainer, with an opening in the head through which the retainers are released to permit opening of the windows.

CHARLES GAYLORD DEMING.
